[57] CLAIM

The ornamental design for a computer, as shown and described.

DESCRIPTION

FIG. 1 is a front elevation view of the computer showing my new invention;

FIG. 2 is a left side elevation view thereof;

FIG. 3 is a top plan view thereof; and,

FIG. 4 is an enlarged top front and right side perspective view thereof.

The undisclosed rear and bottom view are unornamented and the broken lines are shown in FIGS. 2 and 3 for illustrative purposes only and claim no part of the claimed design.

FIG. 2

FIG. 3

FIG. 1

FIG. 4
